JESSE B. GARBER, OF SALEM, OHIO, ASSIGNOR TO THE DEMING COMPANY, OF SALEM, OHIO, A CORPORATION OF OHIO.

PUMP.

Application filed December 4, 1922. Serial No. 604,712.

This invention is concerned with hydraulic pumps of the reciprocating heavy duty type such as are used in mines and under like conditions.

The general object of the present invention is the provision of a novel durable double-acting pump of the character referred to wherein the mechanism may be compactly arranged and provided with interchangeable parts positioned within a readily separable casing whereby the particular parts of the pumps which are subjected to unusual wear, may be interchanged in the pump construction with other similar parts not subjected to wear.

A more specific object of my invention is the provision of a double-acting uniflow pump having a piston and valve construction embodying the use of a minimum number of interchangeable piston members and valve members whereby the manufacturing of the pump may be greatly simplified and a comparatively low production cost thereof may be attained.

An additional object of the present invention is the provision of a novel stuffing box construction adaptable for use in such a pump construction whereby unusual gland pressures upon the piston rod may be obviated while maintaining proper seal about the rod to prevent leakage.

Other objects of the invention will become apparent from the following description, taken in connection with the accompanying drawings. The essential features will be summarized in the claims.

In the drawings, in Fig. 1, I show a plan view of the embodiment of my invention; Fig. 2 is an end view as observed from the stuffing box or power end of the pump; Fig. 3 is a central cross sectional view taken through the pump substantially along the line 3—3 of Fig. 2; Fig. 4 is a transverse cross sectional view taken through the pump substantially along the line 4—4 of Fig. 3; Fig. 5 is a cross sectional telescopic view taken through the center of the pump; Fig. 6 is a cross sectional view showing an alternate arrangement of the parts comprising the double piston construction.

My invention contemplates a heavy duty pump construction adaptable for use in mines and for other heavy duty uses in isolated regions, such for example as irrigation projects, where heavy duty pumps are

in constant use and a high percentage of solid matter is carried through the pump by water passing therethrough. Pumps used under such conditions are subjected to extreme wear. Accordingly I have arranged the structure of my pump in such a manner that the members comprising the piston construction and those valves which are subjected to the greatest wear, may be readily interchanged, with parts not subjected to such wear.

Describing my invention by the use of reference characters, I show in Fig. 3 a double-acting hydraulic pump comprising a cylindrical casing 8, an end member or head 9 removably secured thereto and a removable end member 10, shown as having a suction inlet 7 and a discharge outlet 7^a. The casing members may be suitably flanged and attached to each other by bolt members 11 and 12, whereby the end members may be readily removed to permit access to the valves. In addition to the bolt members 11 and 12, I provide exteriorly disposed parallel bolts 14 extending along the sides of the casing member 8 and engaging suitable bosses 15 and 16 formed on the end members 9 and 10 respectively; the bars 14 being of sufficient strength to maintain the casing members in sealed relation.

The casing member 8 may have a suction chamber 17 formed therein extending longitudinally thereof and establishing communication between the suction inlet chamber 18 formed in the end member 10 and a similar chamber 19 formed in the head member 9 while the bottom thereof may have a passageway communicating with a discharge chamber 21 suitably formed in the end member 10.

Removably positioned within the casing 8 may be a cylinder 22 formed, if desired, of a very durable metal, such as bronze, and properly flanged, as at 23, to engage bored flanges 24 formed in the casing. The size of the engaging flanges may be such as to provide an annular space 25 between the wall of the casing and the cylinder wall, whereby communication may be established between the interior of the cylinder and the compression chamber 20, through exhaust ports 26 shown circumferentially arranged in the cylinder wall midway of its two ends.

The end casing member 9 may have the inner wall 26 thereof properly formed to en-

gage one flanged end of the cylinder, thereby properly positioning the cylinder longitudinally of the pump while the other end member 10 may have a similar wall 27 suitably formed to engage the other end of the cylinder; these respective walls of the end members having a tight fit with the end of the cylinder to prevent leakage from the cylinder to the suction or exhaust chambers of the pump. Extensions of these inner walls may also carry intake valve seats, as will be presently described.

The wall 26 may be also formed to receive an annular flanged intake valve member 28 which may be maintained in fixed relation thereto by a sleeve member 29 suitably threaded to engage in an interiorly threaded inwardly projecting boss 30 integrally formed on the end casing 39. The sleeve 29 may project inwardly from the valve member 28 to afford a bearing for a slidable valve closure disk 31 of resilient material and an annular ribbed disk 32. Spring members 33 serve to seat these valves.

The construction of the valve member 28, the sleeve 29, the valve closure disc 31, the pressure disc 32 is such that another intake valve embodying in its construction corresponding parts which are interchangeable with the described valve parts may be disposed at the other end of the cylinder and supported by the end casing wall 27. As shown in Fig. 3, the sleeve member 29 in this case, however, engages an exteriorly threaded boss 34 associated with the packing box construction of the pump and is suitably bared to also serve as a piston rod bearing.

To further carry out the idea of a minimum number of interchangeable, replaceable parts, I construct the piston with parts having the same design as the parts comprising the valves hereinbefore described. As shown in Fig. 3, the piston may comprise sleeve members 29^a interiorly threaded, however, to engage the inner threaded end of the piston rod 36 and maintained in proper position thereon by any convenient means, such as a cotter pin 37 extending through the rod and engaging adjacent slots formed in the abutting ends of the sleeves 29^a and pairs of valve members 28 and 28^a mounted on the sleeves.

The sleeves 29^a are arranged to slidably support outlet valve discs 31, the valve discs being maintained in contact with opposite faces of the two valve members 28 comprising the piston structure. It will be thus seen that the piston structure may be formed by placing two of the interchangeable valve members 28 with their flanged ends disposed away from each other, whereby the flanges may compress packing rings 40 into sliding engagement with the cylinder wall.

It will be noted that such a piston con-

struction provides extra valve members 28 which may be taken out of the piston structure and interchanged with one of the intake valve members 28 carried by either of the end casing members 9 or 10. Since the surface 28^a of the intake valve member is subjected to the greatest wear when being used as an intake valve, it nevertheless does not function nor is it subjected to any wear when used in the piston structure. Likewise by reversing the valve closure member 31 an unworn valve surface may be obtained.

In Fig. 6, I show a modified form of piston construction where the idea of interchangeable piston and valve parts is maintained, but the construction is such as to provide a piston of the so-called skirt type. To obtain this construction the members 28 are assembled on the sleeves 29^a with the flange of one adjacent the unflanged end of a second member 28, there being an annular ring 54 supporting the annular or skirt portion 55 of the piston which may be formed of leather or other suitable material, the radial portion 55^a being gripped between the adjacent ends of the members 28.

To obtain a highly efficient stuffing box construction which will be subjected to the minimum amount of wear, I associate the stuffing box structure with the suction chamber of the pump in such manner that only a minimum pressure is required upon the stuffing box gland to maintain a proper seal between the reciprocating piston rod and the pump casing. As shown in Fig. 3, this may be obtained by providing a passageway 41 extending into the suction box wherein there is a drain chamber or trap 42 formed by inserted coniform metallic washer members 43 spaced apart by lugs 44 formed thereon. Suitable packing 46 may be provided between the inner end of the stuffing box and the washer and similar packing 47 between the washers and the outer end of the stuffing box. The usual stuffing box sleeve 50, acted upon by a nut 51 in threaded engagement with the casing 10, affords a means for compressing the packing 46 and 47 into engagement with the piston rod 36.

It will be thus seen that any leakage from the interior of the cylinder along the shaft will be trapped within the stuffing box and will be drained back into the suction chamber 18 through the passageway 41. Such a stuffing box construction, I find, will be very effective without resorting to applying any undue compressing of the packing 46 and 47 by tightening the nut 50 and sleeve 51 inasmuch as the leakage intentionally permitted along the shaft in order to save the packing is returned to the pump by suction through the passageway 41.

From the foregoing description it is apparent that the action of the pump is based

on the uniflow principle, and its operation is as follows:—When the pair of pistons are moved from the right to the left, the right piston is drawing water from the suction chamber 18 through the valve at the power end of the pump and the valve at the left end of the pump is closed. The water thus entrapped in left half of the cylinder is under compression and consequently, the outer 5 let valve in the left piston is open. The left piston is therefore inactive by this movement when water is being forced from the cylinder by the right piston through the port openings 26 into the exhaust chamber 20. 10 Upon a reversing movement of the piston rod, the valve in the piston to the left closes and the intake valve at the power end of the pump also closes. This movement of the pistons towards the power end of the 15 pump results in the left piston compressing the entrapped water in the right half of the cylinder as it passes through the valve in the right piston; water in the meantime being drawn from the power end of the pump through the passageway 17 and then through 20 the intake valve at the left end of the pump.

If solid matter such as lumps of coal, small rocks, etc., pass through the intake valves, the presence thereof within the cylinder will not result in damage to the pump and will eventually be shifted to the outlet 30 parts by the movement of the pistons.

From the foregoing description, it is obvious that my invention provides a pump 35 construction of the double acting piston valve type having the characteristics of a minimum number of durable, replaceable parts, the valve parts subject to wear being interchangeable with members comprising 40 the pistons, the construction of the casing being such as to permit convenient separation of the casing members to interchange these parts after they have become worn when functioning as valve parts. In other 45 words, I embody within the pump construction spare valve parts in the piston construction and piston rod bearing parts in the valve construction which are available at all times to any ordinary pump operator in 50 the event of accident or break-down, irrespective of the remoteness of locality or transportation facilities. I furthermore provide a novel stuffing box construction in the pump which affords the greatest degree 55 of efficiency in preventing leaks and in addition thereto is of such construction that the packing glands are effective in preventing leaks without being compressed in the usual manner to an extreme degree, thereby 60 insuring long service. I obtain the additional advantage of a simple, compact, easily manufactured double acting pump based on the uniflow principle.

Having thus described my invention, I 65 claim:—

1. In a pump of the character described, the combination with a valve and a piston rod, of a member externally supporting said valve and another member of similar size and shape internally supporting said piston 70 rod, said two members being interchangeable.

2. In a pump, the combination of a tubular member, a piston rod guided by the internal portion of said member, a valve slidably mounted on the external portion of 75 said member, a duplicate of said member in another portion of the pump and a valve mounted on said duplicate.

3. In a pump of the character described, 80 the combination of a casing having an inlet and an outlet, a cylinder within the casing having an outlet port intermediate its ends, said casing having a portion surrounding the cylinder and provided with an opening 85 connecting the space about the cylinder with the outlet, said casing also having passageways from the inlet to the opposite ends of the cylinder, intake valves positioned at the 90 ends of the cylinder, and a pair of pistons propelled within the cylinder and respectively on opposite sides of the outlet port.

4. In a double acting pump of the character described, a cylinder, a casing surrounding the cylinder, to form a discharge, 95 an intake valve disposed at each end of the cylinder, said casing having passageways communicating with said intake valves, a piston rod, a pair of pistons mounted thereon, and compression valves embodied in the 100 piston structure.

5. In a double acting pump of the character described, a cylinder having outlet ports formed intermediate its ends, a casing surrounding the cylinder, an intake 105 valve disposed on opposite sides of the cylinder ports, said casing having passageways communicating with said intake valves and said cylinder outlet ports, a pair of pistons mounted thereon, and also disposed on opposite sides of outlet ports and compression 110 valves embodied in the piston structure.

6. In a double acting pump of the character described, a cylinder, a casing surrounding the cylinder, an intake valve mechanism at one end of the cylinder having a valve and a supporting member, an intake valve mechanism disposed at the other end of the cylinder, a piston rod, a pair of pistons mounted thereon, a bearing member for the rod supported by the casing, said bearing member supporting the last mentioned valve and being interchangeable with the member carrying the other intake valve.

7. In a double acting pump of the character described, the combination of a casing having inlet and an outlet, a removable cylinder supported therein, inlet valves disposed within the casing at each end of the cylinder, said casing having passageways 125 130

establishing communication between the inlet and said intake valves and between said cylinder and said outlet, a piston rod, a double piston structure mounted thereon comprising compression valves oppositely disposed and arranged to coact alternately with said inlet valves upon reciprocation of said piston rod, said piston structure comprising a pair of demountable members and adapted to compressibly support packing means in contact with the cylinder wall when placed back to back and being of the same size and shape as the members comprising said intake valves.

8. In a double acting pump of the character described, the combination of a casing having inlet and an outlet, a removable cylinder supported therein, and having a discharge passageway through its wall, a member surrounding the cylinder and leading to the discharge passageway, a suction passageway leading from the ends of the cylinder, inlet valves supported by separable end members comprising the casing and disposed at each end of the cylinder, a piston rod, a double piston structure mounted thereon comprising compression valves oppositely disposed and arranged to coact alternately with said inlet valves upon reciprocation of said piston rod.

9. A double acting pump of the character described, comprising a casing formed by a central cylinder supporting member and two end members detachably secured thereto, in combination with a cylinder removably positioned within said central casing member and having the ends thereof engaged by said end casing members, intake valves supported by the end members and the ends of the cylinder, said central casing member having a passageway establishing communication between suction chambers formed in the end members, and an annular passageway establishing communication between a compression chamber formed in one of the end members and an outlet port formed in the cylinder wall intermediate its ends.

10. A double acting pump of the character

ter described, comprising a casing formed by a central cylinder supporting member and two end members detachably secured thereto, a cylinder removably positioned within said central casing member and having a longitudinal space between the casing member and the cylinder wall, said central casing member having a passageway establishing communication between an inlet formed in one of the end members, and another passageway establishing communication between said longitudinal space and an outlet formed in one of the end members.

11. In a pump of the character described, the combination of a cylinder having outlet ports formed intermediate its ends, a pair of pistons adapted to reciprocate within the cylinder on each side of said outlet ports, a piston rod therefor, and coaxially disposed intake valves positioned at each end of the cylinder, one of the valves surrounding the piston rod, said valves having stationary seat members which are duplicates of and interchangeable with members comprising the pistons.

12. In a pump of the character described, the combination of a cylinder having outlet ports formed intermediate its ends, a pair of pistons adapted to reciprocate within the cylinder on each side of said outlet ports, a piston rod therefor and intake valves positioned on each side of the cylinder outlet ports, said valves comprising stationary seat members which are duplicates of and interchangeable, and adapted to surround the piston rod.

13. In a double acting pump of the character described, the combination of a valve including a movable disk and a seat member therefor having a cylindrical portion terminating in an edge flange, a piston rod and a piston thereof comprising two duplicates of said seat member, a packing mounted on the cylindrical portion thereof and retained by such edge flanges.

In testimony whereof, I hereunto affix my signature.

JESSE B. GARBER.
